UNITED STATES PATENT OFFICE.

CHARLES A. MAY, OF TRENTON, NEW JERSEY, ASSIGNOR TO THE MAD-DOCK POTTERY COMPANY, OF SAME PLACE.

DESIGN FOR A COVER-DISH.

SPECIFICATION forming part of Design No. 23,077, dated February 20, 1894.

Application filed January 17, 1894. Serial No. 497,210. Term of patent 7 years.

To all whom it may concern:

Be it known that I, CHARLES A. MAY, a citizen of the United States, residing at Trenton, in the county of Mercer and State of New Jersey, have invented and produced a certain new Design for Dishes; and I do hereby declare the following to be a full, clear, and exact description of the invention, such as will enable others skilled in the art to which it applies to make and use the same.

In the accompanying drawings which form part of this specification Figure 1 represents a side view of a covered dish with the cover raised above the dish and embodying my design; Fig. 2 a top plan view; Fig. 3 a vertical section of part of the dish and cover; Fig. 4 a section on line $x-x$ through the cover.

The following are the leading features of the design.

- o The dish A and its cover B are elliptical in form and the dish is provided with a swell or rounded portion a on its periphery which projects out beyond the vertical plane of the rim of the dish and at its lower end vanishes in the inclined part b , which continues to the rim c on which the dish rests. On the sides and ends of the dish are panels d and e and in the latter are the handles C , and between said panels are curved concavities ff with beads g g on each side of the concavities and grooves h and convex portions i adjacent to each of the beads, and all of said parts merge into or van-

ish in the inclined surface b and are surrounded by a bead k which forms the upper rim of the dish. The handles C are in the 35 form of ornate scrolls bent downward on opposite sides of the dish. The cover B is slightly dome-shaped, has panels l on the sides which are composed of convex surfaces m and n with an intervening concavity o which vanishes toward the end panels p of the cover, which end panels are convex. Between the panels l and p are concavities, beads, grooves and convex surfaces which correspond with like parts in the dish, and they all vanish in 45 the plain surface of the cover before the swell or convex surface n is reached, and the cover is scalloped at q in the rim at the outer end of the concave and convex surfaces described, and is provided with a raised and twisted or 50 curled ornate handle D , both ends of which form a junction with the cover on one side of the transverse center of the cover and are embellished by a stem and foliage shown at s extending down toward the panel p . 55

What I claim is—

The design for a dish substantially as herein shown and described.

In testimony whereof I affix my signature in presence of two witnesses.

CHARLES A. MAY.
